(57) CLAIM

The ornamental design for a drill stand, as shown and described.

DESCRIPTION

FIG. 1 is a perspective view taken from the top, front and right side of a drill stand showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective illustrative view of the drill stand of which the manual wheel-handle is installed on the back side of the said stand; and,

FIG. 9 is a front view of the drill stand illustrating the electric drill is mounted on the movable plate of the drill stand.

The broken line showing is for illustrative purposes only and forms no part of the claimed design.
